2 SHEETS—SHEET 2.

UNITED STATES PATENT OFFICE.

JOHN C. SLOCUM, OF COLUMBUS, OHIO, ASSIGNOR TO JOSEPH A. JEFFREY, OF COLUMBUS, OHIO.

CLAM-SHELL BUCKET.

No. 813,528.

Specification of Letters Patent.

Patented Feb. 27, 1906.

Application filed July 8, 1904. Serial No. 215,548.

To all whom it may concern:

Be it known that I, JOHN C. SLOCUM, a citizen of the United States, residing at Columbus, in the county of Franklin and State of Ohio, have invented certain new and useful Improvements in Clam-Shell Buckets, of which the following is a specification, reference being had therein to the accompanying drawings.

10 This invention relates to an improvement in clam-shell buckets.

Figure 1 is a side elevation of a bucket embodying my improvements. Fig. 2 is a plan view of the same. Fig. 3 is an end elevation. Fig. 4 shows the scoops or bucket portions when separated.

In the drawings, A A' represent the scoop or bucket sections oppositely disposed relative to each other.

20 B B' are pairs of levers arranged one pair at either side of the mechanism and adapted to support the rear ends of the bucket-sections and to transmit power thereto for closing said sections together. Preferably each 25 of these levers consists of a relatively straight upper portion *b* and a curved lower portion *b'*, each lever being loosely mounted on the shaft B², which extends from one side of the mechanism to the other and is suitably held 30 against lateral displacement relative to the said levers.

35 B² B²' are shafts extending transversely across the upper rear corner of each scoop or bucket-section and secured against lateral displacement relative to the side walls of the scoops. The lower end of the curved portion of each of the levers B B' is loosely mounted 40 upon one of the said shafts B² in such manner as to support the rear ends of scoops or bucket sections and also is adapted for applying power thereto for closing the buckets, as will be hereinafter described.

45 C C' C' C'' are pairs of links pivotally connected at their lower ends to the upper inner corners of the scoops or bucket sections A A', respectively, as shown at *c c'*. The pair of links C C are pivotally connected at their upper end to the upper portions *b* of the levers B' at points *c'* in a horizontal plane above the 50 horizontal plane of the pivotal connection B' of the operating-levers, and the other pair of links C' C'' are pivotally connected at a corresponding point *c''* to the upper portions *b* of the levers B B.

F F' are bars or spreaders extending between the upper ends of each pair of levers B B' B' B'', respectively, and upon the ends of which the levers B B' and B' B'', are loosely mounted, said spreaders being suitably held against lateral displacement relative to said levers. Near their centers these bars F F' are provided with pockets, as indicated at F², and in said pockets, upon shafts F² extending vertically through both sides of said pockets and secured thereto, are loosely-mounted pulleys or sheaves D.

G represents the supporting-frame for the lever mechanism and for the guiding-pulleys for the operating-ropes. Preferably this frame consists of a tubular bearing portion 70 G', loosely mounted on the shaft B², and the upwardly-extending arms G² G²'.

H H' are transversely-arranged shafts extending between and mounted in the upper ends of the arms G² and G²'. I I' are pulleys 75 or sheaves loosely mounted upon said shafts H H', respectively, and adapted to guide the opening-ropes K K', respectively, which are secured at their lower ends to the shafts B².

L L' are sheaves or pulleys loosely mounted on the shafts H H', respectively, near the opposite ends of said shafts and are adapted to receive and guide the closing-ropes M M', the former of which passes around the pulley D, carried by the cross-bar F, and has its end 85 rigidly secured at *m* to the arm G² of the supporting-frame. The other closing-rope M' extends around the pulley L' and the pulley D, carried by the connecting-bar F', and has its end rigidly secured at M' to the arm G²' of 90 the supporting-frame.

In operation to open the bucket power is applied through the ropes K K', causing the bucket-sections to swing outwardly around the axis of the shaft B². During this movement of the bucket the curved or lower portion *b'* of each of the operating-levers approaches the straight or upper portion *b* of the lever associated with it. This movement of the upper portion of each pair of levers 100 relative to the lower portion as the heel ends of the buckets swing away from each other causes the front ends of the buckets under the control of the links *c c'* to impart a peculiar and desirable course of travel of the front ends of the bucket. In scooping up or loading material into clam-shell buckets it is desirable that the bottoms of the scoop or

bucket sections as they approach each other should travel for a considerable distance in substantially horizontal lines under the material in which the bucket is working. By connecting the front end of each bucket-section through the links $c c$ or $c' c'$ to the upper portions $b b$ of the links which control the movements of the rear ends of the opposing bucket I attain the desired horizontal travel of the bottom of each scoop or bucket section. In order to close the bucket, power is applied through the ropes $M M'$ to the upper ends of the levers $B B'$, drawing them toward each other and at the same time causing their lower ends to swing inwardly, the travel of the rear ends of the buckets being controlled by the lower end of the lever to which they are connected, the course of travel of their front ends being controlled by the movement of the upper portion of the other lever transmitted through one of the said pairs of connecting-links $C C' C' C$.

What I claim is—

1. In a grab-bucket the combination with two opposing bucket-sections, of the operating-levers each having its lower end pivotally connected to the rear portion of one of the bucket-sections, the levers being arranged to cross each other intermediate of their ends, the links connecting the front portions of each of said bucket-sections to the operating-lever for the opposing bucket-sections, and the ropes for closing the bucket-sections together connected to the upper end of said operating-levers and adapted to draw the said ends toward each other.

2. In a grab-bucket the combination with a pair of opposing bucket-sections, of the operating-levers each connected at its lower end to the rear portion of one of said bucket-sections, the levers for the respective sections crossing each other at points intermediate of their ends, the links connecting the front portions of each bucket-section with the operating-lever of the opposing bucket-section, the supporting-frame, the rope-guiding devices on said frame and the closing-rope connected to the upper end of each of said operating-levers and passing around said guiding devices on the frame and adapted to draw the upper ends of said levers together.

3. In a grab-bucket the combination with two opposing bucket-sections, of a transversely-arranged shaft, the operating-levers mounted on said shaft at points between their respective ends and having their lower ends connected with the said bucket-sections, the links connecting said bucket-sections with the operating-levers of the opposing bucket-sections, the frame having a bearing for said shaft, the rope-guiding devices carried by said frame and the closing-ropes for the mechanism extending around said guiding devices and connected with the upper ends of said levers.

4. In a grab-bucket the combination with two opposing bucket-sections of the operating-levers, each having its lower end connected to the rear portion of one of said bucket-sections, the said levers crossing each other at points between their respective ends, links connecting the front ends of each of said bucket-sections with the operating-lever for the opposing bucket-section, the rope-guiding devices supported between said operating-levers and the ropes each connected to the rear of one of said bucket-sections and extending around said guiding devices. 70

5. In a grab-bucket the combination with a pair of opposing bucket-sections, of the operating-levers pivotally connected together intermediate of their ends and each connected at its lower end to the rear of one of said bucket-sections, the links connecting the front end of each of said scoops or bucket-sections with the operating-lever for the opposing section, the rope-guiding devices secured to the upper ends of the operating-lever, the supporting-frame, the rope-guiding devices secured to said frame and the ropes associated with said guiding devices and arranged to draw the upper ends of said operating-levers toward each other. 80

6. In a grab-bucket the combination with the two opposing bucket-sections, of the transversely-arranged shaft, the operating-levers each connected at its lower end to the rear end of one of said bucket-sections and mounted between its ends upon said transverse shaft, the frame having a bearing for said shaft, the rope-guiding devices on said frame and the ropes having their ends secured to said frame, connected with the upper ends of said operating-levers and extending around said guiding devices. 90

7. In a grab-bucket the combination with a pair of opposing bucket-sections of the transverse shaft, the operating-levers mounted on said shaft at points intermediate of their ends and having their lower ends connected with the rear ends of said bucket-sections, the links connecting the front ends of each of said bucket-sections with the operating-lever for the opposing section, the frame having a bearing for the said shaft, the rope-guiding devices supported by each of said operating-levers near its top, the rope-guiding devices supported on said frame and the ropes extending around said guiding devices and secured to said frame. 100

8. In a grab-bucket the combination with two opposing bucket-sections, of a pair of levers pivotally connected together intermediate of their ends, each of said levers being connected at its lower end to the upper rear corner of one of said bucket-sections, the links each pivotally connected at its lower end to the upper front corner of one of said bucket-sections and at its upper end to the operating-lever for the opposing bucket-section. 110

- tion, the supporting-frame, the rope-guiding devices on said frame, the rope-guiding devices at the upper end of each of said operating-levers, and the closing-ropes, each secured at one end to the supporting-frame and extending around one of the guiding devices on the operating-levers and one of the guiding devices on said supporting-frame.
9. In a grab-bucket, the combination with two opposing bucket-sections, of means connected to the rear end of each of said bucket-sections for controlling the closing movements of said bucket-sections, and independent means also connected with the rear ends of each of said bucket-sections for controlling the opening movements thereof.
10. In a grab-bucket, the combination with two opposing bucket-sections, of means connected to the rear end of each of said bucket-sections for controlling the opening movements of the buckets, means connecting the front ends of each of said buckets with the said means for controlling the opening of the bucket-sections, and independent means for controlling the opening movements of the bucket-sections.
11. In a grab-bucket, the combination with two opposing bucket-sections, of means connected to the upper rear corners of each bucket-section for controlling the closing movements of the bucket-sections, and independent means also connected to the upper rear corners of said bucket-sections for controlling the opening movements thereof.
12. In a grab-bucket, the combination with two opposing bucket-sections, of means connected to the upper rear corners of each bucket-section for controlling the closing movements of the bucket-sections, independent means also connected to the upper rear corners of said bucket-sections for controlling the opening movements thereof, and means for controlling the front ends of each of said bucket-sections, said latter means being connected with and controlled by the means for closing the bucket-sections together.
13. In a grab-bucket, the combination with two opposing bucket-sections, of the crossed operating-levers, each connected at its lower end to the rear end of one of said bucket-sections, the links connecting the front ends of said bucket-sections with the operating-lever connected to the rear end of the opposing bucket-section, means connect-
- ed with said operating-levers for controlling the opening movements of said buckets, and independent means connected with said operating-levers for controlling the closing movements of said buckets.
14. In a grab-bucket, the combination with two opposing bucket-sections, of the crossed operating-levers, each having its lower end pivotally connected to the rear end of one of said bucket-sections, the links, each connected at its lower end to the front end of one of said bucket-sections, and its upper end to the lever which controls the rear end of the opposite bucket-section, the ropes for controlling the opening movements of the bucket-sections, and the ropes connected to the upper ends of said operating-levers for controlling the closing movements of said bucket-sections.
15. In a grab-bucket, the combination with two opposing bucket-sections, of the operating-levers, each having its lower end pivotally connected to the rear portion of one of said bucket-sections, the levers being arranged to cross each other intermediate of their ends, the links connecting the front portion of each of said bucket-sections to the operating-lever for the opposing bucket-section, means for controlling the opening movements of said bucket-sections, and independent means connected with said operating-lever for controlling the closing movements of said bucket-sections.
16. In a grab-bucket, the combination with two opposing bucket-sections, of crossed operating-levers, each having its lower end pivotally connected to the rear end of one of said bucket-sections, the links, each connected at its lower end to the front end of one of said bucket-sections and at its upper end to the operating-lever for the opposing bucket-section, ropes for controlling the opening movements of said bucket-sections, each connected to the operating-levers for one of said bucket-sections near their lower ends, and means for controlling the closing movements of said bucket-sections connected with the upper end of said operating-levers.

In testimony whereof I affix my signature in presence of two witnesses.

JOHN C. SLOCUM.
